UNITED STATES PATENT OFFICE.

JOHN F. STANDISH, OF WINTHROP, MASSACHUSETTS, ASSIGNOR TO UNITED SHOE MACHINERY CORPORATION, OF PATERSON, NEW JERSEY, A CORPORATION OF NEW JERSEY.

ART OF ATTACHING HEELS.

Application filed January 12, 1922. Serial No. 523,686.

To all whom it may concern:

Be it known that I, JOHN F. STANDISH, a citizen of the United States, residing at Winthrop, in the county of Suffolk and State of Massachusetts, have invented certain Improvements in the Art of Attaching Heels, of which the following description, in connection with the accompanying drawings, is a specification, like reference characters on the drawings indicating like parts in the several figures.

This invention relates to the attachment of heels to shoes, it concerning particularly the securing of such yieldable heels as those of rubber, which have, prior to their attachment, a concave form.

A well-known practice in connection with the machine-nailing of rubber heels involves surrounding the heel with a ring or form, provided with an opening into which the heel substantially fits, so that it is prevented from expanding laterally under the pressure which is applied in the heeler. This prevents the deformation of the heel and the consequent carrying of the nail-receiving openings and washers out of alinement with the openings in the die-block of the apparatus. When, however, such a procedure is applied to the concave type of heels, of which there are several slightly differing forms in use, difficulties arise. These heels are usually concavo-convex, having a depression at the side which is to contact with the outer surface of the heel-base, and being correspondingly rounded outwardly at the tread-face. These heels, in attachment, are flattened under pressure upon their bases, to bring the inner and outer surfaces into substantial parallelism and produce close contact between the peripheral edge of the heel and the base. If such a heel be confined closely in the ring previously mentioned, lack of opportunity to expand prevents its flattening, and interferes with its proper application. If, on the other hand, some lateral play of the heel is permitted in the ring, it will not be located definitely, and its openings may not be alined correctly with the drivers. The present invention overcomes such difficulties by a novel method of procedure and a device for use in carrying out this method.

Broadly considered, my improved method comprises the steps of relatively positioning a heel and the receiving surface of the shoe,

applying pressure to bring a portion only of the inner surface of the heel, as at its margin, and said receiving surface into contact, and, while driving nails to attach the heel to the shoe, bringing more of these co-operating surfaces into contact, preferably at this time completing this contact and as a result of the simultaneous action of the heads of the nails upon a contact member in the heel. Said heel is best held initially against lateral expansion, so that it may be definitely located and pressure applied without distortion which will carry the heel-openings away from the die-block-openings, this holding effect preferably continuing until the attaching nails have entered the heel-base, and then the heel is freed for expansion, as by the action of the nails, so that it may flatten to its final position.

In another aspect, a feature of the invention resides in a holding device which may be used in carrying out my improved method. This consists of a member provided with a heel-receiving depression, having walls of different heights respectively arranged for contact with different peripheral portions of a heel. In the initial step of positioning and applying the clamping pressure to the heel, the walls of greatest height retain the heel against expansion, and then, as the pressure continues to complete the engagement between the heel and receiving surface, the walls of less height allow the heel to be freed and to expand, assuming its final, flattened form.

In the accompanying drawing,

Figure 1 illustrates in vertical section, taken upon the longitudinal axis of the shoe operated on, a machine equipped with my novel heel-holding device and generally arranged for the performance of my improved method of heel-attachment, the parts being in the relation for the application of pressure:

Fig. 2 is a transverse section through the heel and holder;

Fig. 3 is a longitudinal section similar to Fig. 1, showing the final step of attachment;

Fig. 4 illustrates the heel-holding member in perspective; and

Fig. 5 is a perspective view of one of the forms of heel to which my invention is applicable.

The type of heel in connection with which

this invention is especially useful is illustrated at H in Fig. 5 of the drawing. This is in the form of a lift of rubber or other yieldable compound, which at its inner side 5 10 is concave, and correspondingly convex at its outer tread-surface 12. At the peripheral edge, the inner surface has points of greatest normal upward curvature, or that existing before the heel is applied to the 10 shoe, at the ends 14, 14 of the breast and at the extreme, central rear portion 16. Between these points, the edge curves downwardly to points 15 of minimum height. At the tread-surface of the heel are openings 18 to receive the attaching nails, and molded in the body of the heel, with their openings in alignment with the openings 18, are washers 20, or other contact members, as sheets of metal or dense fabric, for 15 engagement by the heads of the nails. When the heel is applied, the curved body becomes flattened, so that the inner surface 10 is in substantial contact with the entire outer surface of the receiving base, 20 while the tread-surface 12 of the heel is parallel thereto. The peripheral edge is then perpendicular to these surfaces 10 and 12.

Such heels have, as far as I am aware, always been attached by hand, the workman positioning the heel upon the base, placing the nails in the openings 18, and then, still holding the heel in its symmetrical relation to the base, driving the nails to draw the heel, by the engagement of the nail-heads with the washers, to its final, flattened position. In thus operating, no preliminary or clamping pressure is applied. The difficulties already mentioned have stood in the way of machine-attachment of these concave heels, as this has been customarily practiced. Used in accordance with my invention, however, any heelng machine may be successfully employed for nailing such heels. Portions of an apparatus similar to that illustrated in Patent No. 1,157,688, Glidden, October 26, 1915, appear in the drawing, especially in Fig. 1. At 30 is shown a die-block having openings 32 to receive the drivers 34 mounted upon a reciprocating plate 36. The shoe S, to the heel-base 22 of which a concave heel-lift H is to be applied, is placed upon a jack 38, arranged to swing from a receiving position 35 at the front of the die-block to that illustrated in Fig. 1, in which the work is ready for the nailing operation. The jack and die-block have a relative movement toward and from each other, by virtue of which the shoe may be applied to the jack and brought into position over the openings 32 during the period of separation, and then, as the two elements approach, pressure will be applied to clamp the heel H, supported upon 40 the die, against the base 22, preventing lateral

displacement and preparing the work for the driving of the nails, which is effected by the upward travel of the drivers 34. Nails N, having heads 24, are supported in the die-block-openings upon the ends of 70 the drivers, having been delivered manually or by a suitable loading mechanism, not illustrated.

Secured upon the upper side of the die-block, with openings 40 in alignment with 75 the block-openings 32, is a holder member 42, having in its upper face a heel-receiving depression 44, the bottom wall of which possesses a curvature substantially that of the surface 12 of the heel H. The side walls 80 46, which are shown as vertical, have portions of maximum height at 48, these corresponding to the sides of the heel at 15. The walls 46 are of minimum height at 50, or at the points corresponding to those designated upon the heel as 14 and 16. As illustrated, the walls at 50 merge into the upper surface 52 of the member 42, thus becoming of zero height. Such a holder may conveniently be produced by casting, employing the heel with which it is to be used as a pattern.

In the performance of my improved method, the heel H is placed in the depression 44, which substantially conforms to it, 95 the side walls of the depression at 48 furnishing abutments, which prevent the lateral movement of the heel, while between the points 50, at the breast side and at each side of such point at the rear of the heel, the walls are of sufficient height to hold the heel against movement longitudinally. When the preliminary pressure is applied, it partially flattens the heel, bringing its marginal portions into engagement with the base, as is illustrated in Figs. 1 and 2. The heel and shoe thus being held in proper relation, the drivers 34, upon each of which a nail is resting, rise and simultaneously 100 carry the points of the nails through the heel-openings 18, and the aligned openings of the washers 20 into the base. As this action continues, the nail-heads reach the washers, and by their engagement therewith exert pressure upon the heel to flatten it and, when fully driven, completing its contact with the base, as appears in Fig. 3. At the same time, this driver-action raises the heel out of the holder-depression free from the walls 46, so that it is permitted to expand laterally in the assumption of 110 its final form, thus completing the operation.

Having described my invention, what I claim as new and desire to secure by Letters Patent of the United States is:

1. The method of attaching yieldable concave heels, which consists in relatively positioning a heel and the receiving surface of a shoe, applying pressure to bring a portion 120

only of the inner surface of the heel and said receiving surface into contact, driving nails to attach the heel to the shoe, and bringing more of the inner surface of the heel into contact with the receiving surface.

2. The method of attaching yieldable concave heels, which consists in relatively positioning a heel and the receiving surface of a shoe, applying pressure to partially flatten the heel and bring the marginal portion only of its inner surface into contact with the receiving surface, and simultaneously driving a plurality of nails to attach the heel to the shoe and to further flatten the heel and complete the contact of its inner surface with the receiving surface.

3. The method of attaching yieldable concave heels each provided with a contact member, which consists in relatively positioning a heel and the receiving surface of a shoe, applying pressure to bring a portion only of the inner surface of the heel and said receiving surface into contact, and simultaneously driving a plurality of headed nails through the contact member to attach the heel and by the engagement of the heads with said contact member to bring more of the inner surface into contact with the receiving surface.

4. The method of attaching rubber heels, which consists in holding a heel against lateral expansion, relatively positioning said heel and the receiving surface of a shoe, applying pressure to carry the heel and shoe toward each other, driving nails to attach the heel, and freeing the previously held portion of said heel for lateral expansion during the application of operating pressure.

5. The method of attaching rubber heels, which consists in holding a heel against lateral expansion, relatively positioning said heel and the receiving surface of a shoe, applying pressure to carry the heel and shoe toward each other, driving nails to attach the heel, and utilizing the effect upon the heel of the nail-driving operation to free it for lateral expansion.

6. The method of attaching concave rubber heels, which consists in holding the more concaved portion of a heel against lateral expansion, leaving the less concaved portion free, driving nails to attach the heel to a shoe, and exerting pressure to free the heel for expansion.

7. The method of attaching rubber heels provided with a contact member, which consists in holding a heel against lateral ex-

pansion, relatively positioning said heel and the receiving surface of a shoe, applying pressure to carry the heel and shoe toward each other, and driving a headed nail through the contact member to attach the heel to the shoe, the engagement of the nail-head with the contact member freeing the heel for lateral expansion.

8. The method of attaching yieldable concave heels, which consists in relatively positioning a heel confined against lateral expansion and the receiving surface of a shoe, applying pressure to carry the heel and shoe toward each other with a portion of their adjacent surfaces in contact, and driving nails to attach the heel, to free said heel for lateral expansion and to complete the contact between the adjacent surfaces.

9. The method of attaching concave rubber heels provided with washers, which consists in confining the more concaved portion of a heel against lateral expansion and positioning it with respect to the receiving surface of a heel-base, applying pressure to carry the heel and base toward each other with the less concaved portion of the surfaces in contact with the base, and driving headed nails to attach the heel to the base and by the engagement of the nail-heads with the washers to free the more concaved portions for lateral expansion and complete its contact with the base.

10. A holder for use in attaching rubber heels, comprising a member provided with a heel receiving depression having side walls of different heights at different positions along its periphery, the walls at such different positions being respectively arranged for contact with particular peripheral portions of a heel.

11. A holder for use in attaching concave rubber heels, comprising a member provided with a depression having an inner wall curved to conform generally to the tread-surface of a heel and side walls extending different distances from the curved wall.

12. A holder for use in attaching concave rubber heels, comprising a member provided with a depression having an inner wall curved to conform generally to the tread-surface of a heel and side walls extending different distances from the curved wall, the side walls substantially fitting the periphery of the heel when said heel is in its normal concave form.

In testimony whereof I have signed my name to this specification.

JOHN F. STANDISH.
